UNITED STATES PATENT OFFICE.

FELIX Q. RAST, OF NEW YORK, N. Y., AND CLIFFORD G. PEIRCE, OF MONTCLAIR, NEW JERSEY; SAID RAST ASSIGNOR TO PUBLIC SUPPLY COMPANY, OF NEW YORK, N. Y., A CORPORATION OF NEW YORK.

VENDING-MACHINE.

1,137,715.

Specification of Letters Patent. Patented Apr. 27, 1915.

Application filed July 6, 1914. Serial No. 249,059.

To all whom it may concern:

Be it known that we, FELIX Q. RAST and CLIFFORD G. PEIRCE, citizens of the United States, and residents of New York city, borough of Manhattan, county and State of New York, and Montclair, Essex county, New Jersey, respectively, have invented certain new and useful Improvements in Vending-Machines, of which the following is a specification.

The object of our invention is to provide a simple and efficient means for discharging vendible articles from a vending machine, and to prevent the discharge of such articles when spurious tokens are inserted through the coin slot of the machine.

A further object of the invention is to provide improved means to prevent the passage of coins through the coin slot to the devices that cause the coin to eject the articles, during the absence of articles from the corresponding chute for the articles.

Our invention comprises novel details of improvement and combinations of parts that will be more fully hereinafter set forth and then pointed out in the claims.

Reference is to be had to the accompanying drawings forming part hereof, wherein,

Figure 1 is a front view, partly broken away, of a vending machine embodying our invention; Fig. 2 is a vertical section on the line 2, 2, in Fig. 1; Fig. 3 is an enlarged detail section looking from the righthand in Fig. 1; Fig. 4 is an enlarged detail of a portion of Fig. 1; Fig. 5 is a section on the line 5, 5, in Fig. 4; and Fig. 6 is a detail section illustrating certain positions of the parts in rejecting a washer.

Similar numerals of reference indicate corresponding parts in the several views.

The numeral 1 indicates a casing of any suitable construction adapted to receive stacks of articles 2 to be vended. Suitable chutes, indicated at 3, are provided to receive said articles, the lower portions of said chutes being shown provided with ledges 3^a to support the articles and spaced apart for the passage of the coins 4 for discharging said articles. At 1^a the casing is shown provided with a coin slot and the rear wall of the casing is shown provided with an inclined guiding ledge 1^b leading to a channel

1^c that leads to a downwardly and forwardly inclined surface 1^d to direct coins into the coin receiving devices to be described. The 55 chute 3 is maintained at a suitable distance from the opposed wall of the casing to provide a passage for the coins therebetween. The side wall of the casing is shown provided with projections 5, above and below, 60 holding the chute 3 away from the side wall of the casing, whereby a space 6 is provided between said chute and wall of the casing for the purpose hereinafter described.

Below the coin chute or channel is a rocking or rotative coin-receiver, indicated generally at 7, and suitably secured upon a transverse rocking shaft 8 journaled in frame 1, shown provided with a handle or knob 9 for operating said shaft. Receiver 7 is shown provided with a coin receiving recess 7^a, upon the bottom 7^b of which a coin may rest, and said receiver is provided in front with spaced abutments 7^c, behind which the lower edge of the coin rests. At 75 10 is a curved finger or pin located at the rear upper portion of receiver 7 adapted to bear against the rear portion of a coin or imperforated spurious token, and to enter a hole in the token. The finger or coin pushing member 10 is curved at its upper edge so that it extends downwardly at an angle toward the receiver below said upper edge. To this end, the upper portion of finger or coin pusher 10 is curved on an arc different 80 from an arc described around the axis of said receiver, so that said edge 10^a may, at its lower portion, enter a hole in the token and as the higher portion of the edge 10^a of said finger engages said edge of the token, 85 when the receiver is rotated, while the upper part of the token is confined behind the lowermost article 2, said token will be caused to rise from the receiver, as hereinafter explained.

Upon receiver 7 is pivotally mounted a weighted tongue 11, shown adapted to play between the abutments 7^c, and extending rearwardly in said receiver in position to be engaged by coins or tokens passing 100 through the coin slot. The weighted portion 11^a of tongue 11 plays freely in a space 12 provided in the receiver behind shaft 8. In the normal or inactive position of said parts,

the upper forward portion of tongue 11 lies approximately in the plane of the upper edges of abutments 7^c, the forward edges of which abutments are shown downwardly inclined at 7^c. The tongue 11 is shown pivotally carried by a pin or shaft 13 carried by the receiver 7, and normally hangs in position to obstruct the passage into recess 7^a to the bottom thereof, but is adapted to be tilted by the weight of a coin to enable the latter to rest upon the bottom 7^b of the recess, as shown in Fig. 2. The receiver 7 may be retained in a normal coin receiving position, as indicated in Figs. 2 and 3, by means of a spring 14 shown connected at one end with said receiver and at the other end with a projection 15 on the casing. The spring 14 normally retains receiver 7 retained against the frame, or an extension thereon, under the coin chute, as illustrated in Figs. 2 and 3, and the lower portion of the inclined part 1^a is shown recessed at 1^c to admit the finger 10. Beneath the receiver 7 the casing is shown provided with a chamber or compartment 16 to receive coins or tokens, forward of which compartment is shown a removable wall 17, located at a suitable distance behind the main cover or door 18, which latter is shown hinged at its lower part at 19, on the casing, and may be held closed by a suitable lock. Between the lower part of cover or door 18 and wall 17 is a space 20, the upper end of which communicates with the delivery end of the chute 3 to receive the articles delivered therefrom, which travel down space 20 and may be removed through the opening 21 shown below the lower end of door 18. The wall 17, being maintained behind the closed door, prevents surreptitious extraction of coins from chamber 16, and for simplicity said wall is shown bearing at its lower edge upon the bottom of casing 1 behind a stop pin 22, and forward of stops 23, the forward edges of said stops being shown beveled to permit wall 17 to slide along the same behind pin 22, and the upper portion of wall 27 is shown bearing against pins 24 on the side walls of casing 1, said wall 17 being shown provided with a projection 17^b, against which the door 18 bears, whereby said wall 17 is retained in position when the door 18 is locked, and may be readily removed when door 18 is swung down, for removal of the coins from chamber 16. The upper edge of wall 17 is shown cut away at 17^a at the front of the upper section of the coin receiver 7, where the coins tilt forwardly. In the space 6 between chute 3 and the wall of the casing is pivoted a lever 25, as at 26, shown having a horizontal portion, one end 25^a of which is adapted to be engaged by the projection 27^a of a weight 27, 65 that rests upon articles 2, said lever having

an upwardly extending portion 25^b from which a laterally extending portion 25^c extends, in position normally retracted from slot 1^a. The position of pivot 26 of lever 25 is such that the latter may normally, by 70 gravity, rest upon stop 29 on chute 3 (Fig. 2) with the end 25^c retracted from slot 1^a, although a spring can be used for the purpose. In the side wall of chute 3 is a vertical slot 3^a leading down below the end 25^a 75 of lever 25, adapted to receive the projection 27^a of weight 27. After the vendible articles 2 are placed in chute 3, the weight 27 is placed in said chute upon the articles, with its projection 27^a passing through slot 3^a. When the lowermost article has been delivered by a coin the weight descends to the ledges 3^a, and thereupon the projection 27^a of said weight engages part 25^a of lever 25, and rocks the latter so that its end 25^c passes across slot 1^a to prevent the insertion of a coin therein, and when the weight is removed lever 25 will swing back away from said slot.

We have illustrated the machine provided 90 with two chutes 3, two coin slots 1^a, and two receivers and their parts, tongues, etc., both said receivers being secured upon shaft 8, adapted to rock together, but it will be understood that the machine may be provided 95 with a single set of devices as described, or with as many such sets as desired. When a proper coin is passed through slot 1^a, it will travel down the coin chute thereunder, and engage the tongue 11 beneath the same, 100 the weight of the coin being sufficient to tilt said tongue to enable the coin to rest upon the bottom 7^b of the receiver, behind the abutments 7^c and forward of the finger or pin 10. When shaft 8 is now rotated, 105 in the direction of the arrow a in Fig. 2, the coin, by being retained between parts 7^c and 10, will push against the rear portion of the lowermost article 2 of the stack above, (the upper edge of the coin passing 110 through a suitable opening in the back of the coin chute), and will force said article outwardly from beneath the stack into the passage 20, whence it will fall to the bottom of casing for removal through opening 21, 115 and the articles will then descend in the chute. Upon return rotation of said coin receiver, if the coin has not dropped therefrom, the upper portion of the coin will engage the lowermost article of the stack and 120 will be dislodged from the receiver 7, and will somersault downwardly into chamber 16. It will be understood that the normal position of receiver 7, (Figs. 2 and 3) is such that the coin will slide properly into 125 the receiver, as shown in Fig. 2, from the inclined surface 1^a, tilting the tongue 11 as stated, and that when the coin is discharged from the receiver said tongue will automatically tilt back to its normal position, as an 130

obstruction to the passage of light weight 5
spurious tokens into the receiver. If a
token whose weight is not great enough to
cause the tongue 11 to tilt so that the token
can enter in the receiver behind its projec-
tions 7^c, said tongue will retain the token
in an upward position, as indicated in
dotted lines in Fig. 3, so that when receiver
7 is rotated, (in the direction of the arrow
a), said light weight token will be retained
on and carried along by tongue 11 with its
upper portion in contact with the lowermost
article 2, and will be caused to slide off
tongue 11 without delivering such article,
it being understood that tongue 11, and re-
ceiver 22 assume different relative positions
when the receiver is rotated, substantially
as indicated in Fig. 6, the tendency of the
tongue being to lift lightweight tokens as
the receiver is rotated, and to keep them
from dislodgment behind the abutments 7^c.
In some instances light-weight spurious
tokens may slide directly off the tongue 11
along the beveled or inclined edges 7^c of
receiver 7.

In case a spurious token having a hole in
its center, such as a washer, (shown at 4^a,
Figs. 4 and 5), be inserted in the coin slot, and
if such token is of sufficient weight to tilt the
tongue 11 so that the token can enter re-
cess 7^a of receiver 7 behind its abutments 7^c,
it may rest in position substantially as
shown by coin 4 in Fig. 2, but in such event
the finger 10 will register with the hole in
the token. When the receiver 7 is now ro-
tated in the direction of the arrow a, the
finger 10 will enter the hole in the token,
and the curved upper portion of said finger
will engage the upper edge of said hole, and
by reason of the lowermost article 2 being
in front of the upper portion of said token,
abutting against the same as a stop, the fin-
ger 10 in moving into the hole in the token
will cause the latter to be pushed upwardly,
partly behind the lowermost article 2, dur-
ing a portion of the movement of the re-
ceiver (Fig. 5), causing the lower edge of
the token to be raised above the abutments
7^c, and causing the token to tilt under-
neath the article 2, and to be carried along
thereunder without dislodging said article.
If such token does not drop off the receiver
during its forward motion, the token will
drop off on the return stroke without dis-
charging an article. The tongue 11 under
the spurious token, on the return stroke of
the receiver, serves to aid in dislodging the
token, should the latter not be dislodged
near the completion of the return stroke.

It will thus be apparent that we have
provided a simple form of mechanism
adapted to discharge articles from a stack
by the action of a proper coin, and to pre-
vent dislodgment of such articles when
spurious tokens of light weight, or having

holes adapted to receive the finger 10, are
inserted in the coin slot, the mechanism be-
ing relatively accurate in operation, not
liable to get out of order and cheap to
manufacture.

Changes may be made in the details of
construction and arrangement of parts
shown and described, within the scope of
the appended claims, without departing
from the spirit of the invention.

Having now described our invention what
we claim is:

1. A vending machine having means to
support a stack of articles therein, a mov-
able coin receiver below said articles and
provided with means to retain a proper
coin with its upper portion in position to
dislodge a vendible article upon one stroke
of said receiver, said receiver having a mov-
able tongue in the path of coins into the re-
ceiver adapted to prevent light-weight
tokens from operatively entering said re-
ceiver, said tongue being in position to re-
tain such tokens in position to be engaged
by the articles to dislodge said tokens from
the receiver when the latter moves for-
wardly.

2. A vending machine having means to
support a stack of articles therein, a mov-
able coin receiver below said articles and
provided with a recess to receive a proper
coin and retain its upper portion in posi-
tion to dislodge a vendible article, said re-
ceiver having a member on one side of the
coin above said recess to coact with the coin,
said receiver also having a movable tongue
extending across the upper part of said re-
cess in the path of coins into the receiver,
to prevent light-weight tokens from opera-
tively entering said recess.

3. A vending machine having means to
support a stack of articles therein, a mov-
able coin receiver below said articles and
provided with a recess to receive a proper
coin, said recess being of less depth than
the coin to expose the upper portion of the
latter to dislodge a vendible article, said re-
ceiver having a member on one side of the
coin above said recess to coact with the coin,
said receiver also having a pivotal weighted
tongue at the upper part of the recess in the
path of coins into said recess adapted to be
moved by a proper coin to permit its en-
trance into the recess with the upper part of
the coin extending above the recess, said
tongue being adapted to prevent light-
weight tokens from operatively entering
said recess.

4. A vending machine having means to
support a stack of articles therein, a mov-
able coin receiver below said articles, said
receiver being provided with a recess and
spaced projections in front of the recess,
said receiver having a member above said
abutments on the side of the coin opposite

4
said abutments to coact with the coin, said receiver also having a pivotal tongue normally extending between said abutments across the upper part of the recess adapted 5 to be tilted by a proper coin to permit its entrance into the recess behind said abutments and adapted to obstruct the entrance of a light-weight token into said recess.

5. A vending machine having means to 10 support a stack of articles therein, a movable coin receiver below said articles, said receiver being provided with a recess and spaced abutments in front of the recess, said receiver having a member above said abutments 15 on the side of the coin opposite said abutments to coact with the coin, said receiver also having a tongue pivotally carried thereby to extend at its free end between said abutments and having a weight- 20 ed portion normally retaining said tongue substantially adjacent to the upper part of said abutments across the upper part of said recess to permit the entrance of a proper coin into said recess and to obstruct the entrance of a light-weight token thereinto.

6. A vending machine having means to 25 support a stack of articles therein, a rotative coin receiver below said articles, said receiver being provided with a recess and spaced abutments for the front of the lower portion of a coin, and a member above said recess and abutments to engage the upper portion of the rear of the coin, said receiver also having a pivotal tongue to obstruct the 30 deposit of light-weight tokens in said recess and adapted to permit the entrance of a coin into said recess in position to be dislodged from the recess when the coin engages an article upon the return stroke of the receiver.

40 7. A vending machine having means to support a stack of articles therein, a rotative coin receiver below said articles, said receiver having a recess for coins provided with an abutment for the front of a coin, 45 and a finger having a curved forward portion extending in a downward and forward direction to enter a hole in a token, the lower end of said finger being wholly within a circumference described around the axis of the 50 receiver, the outer edge of said finger touching such circumference, said supporting means being so located as to retain an article in position in front of the upper portion of said token, to engage said token to cause it 55 to rise out of the receiver.

8. A vending machine having means to support a stack of articles therein, a rotative coin receiver below said articles, said receiver having a recess for coins provided 60 with spaced abutments for the front of a coin or token, a finger having a portion extending in a downward and forward direction to enter a hole in the token adapted to engage said token to cause it to rise out of 65 the recess when the upper part of the token

engages one of said articles, and a tongue movably carried by said receiver to obstruct the entrance into said recess of light-weight tokens and adapted to permit the entrance thereinto of heavier tokens or coins.

9. A vending machine having means to 70 maintain a stack of articles therein, a rotative coin receiver below said articles, said receiver having a forward abutment for the lower part of a coin or token, and a finger 75 behind the coin or token above the abutment, said finger having an upper edge curved downwardly and forwardly on a curve less than a circumference described around the axis of said receiver in position to enter a hole in a token to cause the token to rise out of the receiver when the upper part of the token engages one of said articles.

10. A vending machine having means to 80 retain a stack of articles therein, a rotative coin receiver below said articles, said receiver having a recess and a forward abutment for the lower part of a coin or token, and a finger 85 behind the coin or token above the abutment, said finger having an upper edge curved downwardly and forwardly on a curve less than a circumference described around the axis of said receiver in position to enter a hole in the token to cause the token to rise out of the recess when the upper part 90 of the token engages one of said articles, and a weighted tongue pivotally carried by said receiver and normally in the path of a coin or token into said recess to prevent the entrance of light-weight tokens operatively 95 into the recess and permit the entrance of heavier tokens or coins thereinto.

11. A vending machine having means to 100 retain a stack of articles therein, a rotative coin receiver below said articles, said receiver having a recess and a forward abutment for the lower part of a coin, a finger 105 behind the coin above the abutment, said finger having an upper edge curved downwardly and forwardly on a curve less than the circumference described around the axis of said receiver in position to enter a hole in a token to cause the token to rise out of the recess when the upper part of the token engages one of said articles, and a 110 tongue pivotally carried by said receiver and having a weighted portion depending below said tongue at one side of the support for the receiver, said tongue being normally in the path of a coin or token in said recess to 115 prevent the entrance of light-weight tokens operatively into the recess and to permit the entrance of heavier tokens thereinto.

12. A vending machine having means to 120 maintain a stack of articles therein, a movable coin receiver below said articles and provided with means to retain a proper coin in position to be dislodged from the receiver by coaction with one of said articles on one stroke of the receiver, said receiver having 125 130

means in the path of coins into the receiver adapted to prevent light-weight tokens from operatively entering said receiver, said last named means being in position to retain said 5 light-weight tokens in position to coact with an article to dislodge said tokens from the receiver.

Signed at New York city, in the county

of New York, and State of New York, this 3rd day of July, 1914.
